WARNING SIGNAL UNIT FOR BILGE FLOODING OR THE LIKE

Jack Herscovitz, 5124 Corning Ave., Los Angeles, Calif.

Filed May 5, 1959, Ser. No. 55,787

Term of patent 14 years

(Cl. D72—1)

FIGURE 1 is a top plan view of a warning signal unit for bilge flooding or the like showing my new design; FIGURE 2 is an elevational view thereof; and

FIGURE 3 is a bottom plan view thereof; and

FIGURE 4 is an elevation thereof as seen from the opposite side of FIG. 2 with the bell member omitted for convenience of illustration only.

The essential features of my design reside in the portions shown in full lines.

I claim:

The ornamental design for a warning signal unit for bilge flooding or the like, as shown and described.
